TYPEWRITER FEEDER

Walter O. Critchfield, Shelby, Ohio, assignor to
Shelby Salesbook Company, Shelby, Ohio, a
corporation of Ohio

Application March 17, 1941, Serial No. 383,866

6 Claims. (Cl. 271—42)

My invention relates to typewriters, and has among its objects and advantages the provision of an improved feeder for feeding sheets to the machine.

In the accompanying drawings:

Figure 1 is an elevational view of my invention in association with the cooperating mechanism of a conventional typewriter;

Figure 2 is an end view;

Figure 3 is a view taken from the position indicated by line 3—3 of Figure 2;

Figure 4 is an enlarged sectional view along the line 4—4 of Figure 1;

Figure 5 is a view taken from the position indicated by line 5—5 of Figure 4;

Figure 6 is a view taken from the position indicated by line 6—6 of Figure 4; and

Figure 7 is an enlarged sectional view along the line 7—7 of Figure 6.

In the embodiment selected to illustrate my invention, the feeder 10 is mounted in an upright position at a slight angle to the vertical and is supported through the medium of bars 12 bolted to a bar 14 welded to brackets 16 bolted to the typewriter carriage 18. The upper end margins of the bars 12 are bolted at 20 to a plate 22 bolted at 24 to a bottom plate or wall 26 of the feeder 10.

Plate 26 is provided with right-angular flanges 28 along its two vertical edge margins. A cover 30 is hinged at 32 to one of the flanges 28 which cover normally rests on the two flanges 28 to contact therewith and with the plate 26 to provide a hopper or housing for sheets 34 to be fed to the machine one at a time in lieu of hand feeding. Plate 26 and its flanges 28 function as an open-ended tray for the sheets 34.

The sheets 34 lie flat against the plate 26 and their lower ends rest on flanges 36 which may be welded to the plate. Pointed fingers 38 press the sheets against the wall 26 along their lower edge margins, but the pressure is gentle so that the sheets may be lifted one at a time from the stack without hindrance from the fingers. Both fingers 38 are welded to a shaft 40 rotatably journaled in the side walls 28 and restrained from relative longitudinal movement by reason of key pins 42. One end of the shaft is bent to provide a crank 44 to which one end of a tension spring 46 is attached, the other end of the spring being attached to a pin 48 secured to one of the walls 28. The crank 44 is so arranged with respect to the fingers 38 that the tension of the spring 46 tends to rotate the shaft in a counterclockwise direction when viewing Fig. 4 so that the fingers

are pressed gently against the sheets regardless of the number in the tray. Because of the crank 44, the shaft 40 may be rotated in a clockwise direction against the tension of the spring 46, as when replenishing the sheet supply in the tray.

The invention in the present case is primarily designed for handling sheet units in the nature of carbon interleaved forms. These forms are known in the trade as "Speedisets," "Snap-Outs," etc., and consists of two or more sheets of paper with a one-time carbon paper between each two sheets, the carbon paper being somewhat shorter than the writing paper and all of the sheets, writing paper and carbon paper, fastened together, either by pasting or wire stitching. Fig. 4 illustrates one of the sheets or forms 34 as being removed from the stack in the tray and bent partly about the typewriter platen 50 in the usual manner. The typewriter may be conventional in every respect and includes the usual guide plate 52 which facilitates manual positioning of sheets in position between the platen 50 and the pressure roll 54.

Connected with the cover 30 is a sheet feeding device 56 which removes sheets or forms 34 one at a time from the stack in the tray. Device 56 comprises a flat bar 58 lying adjacent the inner face of the cover 30 and provided with a friction pad 60 at its upper end. Pad 60 may comprise rubber of tapered configuration, with its widest end pointing down, and the pad fixedly secured to the bar 58 by rivets 62.

Two parallel slots 64 are provided in the cover 30, and the bar 58 is provided with two wings 66 which are passable through the slots 64 and each includes a narrow neck 68 which rides freely in its respective slot 64. Normally the necks 68 lie near the ends of the slots 64 and the bottom ends of the wings 66 lie at the lower ends of the slots and are positioned at right angles to the cover 30. A weight 70 is positioned between the wings 66 and secured to the latter by screws 72. Both the wings 66 and the weight 70 are provided with a common curvature 74 arranged to be engaged by the sheets or forms 34 as they are removed from the machine. This curvature deflects the sheets or forms so as to eliminate any obstructing action on the part of the wings and the weight, the latter constituting a grip and a balancing means for the device 34.

Figs. 4, 6 and 7 illustrate the device 56 in its normal position, at which time the lower end of the bar 58 lies between a spring 76 and the cover 30. This spring has its lower end riveted at 78 to the cover 30, and the spring is bent to pro-

vide a deflecting run 80 which facilitates entrance of the bar 58 between the spring and the plate as it is moved from the dotted line position of Fig. 4 to its normal position of Fig. 7. According to Figs. 4 and 7, the device 56 is free to pivot when the bar 58 is moved clear of the spring 76. In other words, the bar 58, in normally paralleling the cover 30, is arranged at an angle to the vertical and leans in the direction of the sheets 34 in the tray, so that the upper end of the bar pivots in the direction of the sheets when the bar is moved clear of the spring 76.

A slight upward movement of the device 56 brings the bar 58 clear of the spring 76. As the bar 58 is moved upwardly, the pivotal motion of the device 56 brings the friction pad 60 into engagement with the outermost sheet or form 34 in the tray. Wings 66 are so spaced as to provide a convenient grip to facilitate manual manipulation of the device 56. Slight pressure on the wings 66 as the device 56 is being moved upwardly to the dotted line position of Fig. 4 will pull the outermost sheet or form 34 from underneath the fingers 38 and slide this sheet or form upwardly to the dotted line position of Fig. 4.

Upon a shaft 82 secured to the wings 66 is mounted a roller 84 arranged to engage the cover 30 when the device 56 pivots to its dotted line position of Fig. 7 or as soon as the bar 58 has been moved out of engagement with the spring 76. The roller 84 is positioned close to the weight 70 and the spacing between the roller and the bar 58 is also such as to provide ample accommodation for the pivotal action of the device 56. The length and weight of the bar 58, together with the friction pad 60, is such as to overbalance the combined weight of the wings 66 and the weight 70. Also, manually releasing the device 56 in its uppermost position permits the device to gravitate downwardly to its normal position. While the device 56 pivots against the sheets or forms 34 in its upward movement relatively to the cover 30, the device is returned to its normal positions of Figs. 4 and 7 by reason of the spring 76 which engages the lower end of the bar 58 and pivots the device to the position illustrated. The roller 84 facilitates dropping of the device 56 after being manually released in its uppermost position.

With the device 56 located in the dotted line position of Fig. 4, one sheet or form has been moved clear of the fingers 38 and the device is then manually released so that it drops downwardly together with the released sheet or form 34. The cover 30 has its lower end extended beneath the plate 26 and is bent to provide a deflecting lip 86 which converges in the direction of the guide plate 52 to provide a throat 88 which guides the sheet or form 34 into accurate position with respect to the pressure roll 54 and the platen 50. The sheet or form is permitted to drop into position so as to be accurately aligned and ready to be turned into typing position in the machine. By reason of this action, the sheets or forms are absolutely straight in the machine, as the side walls 28 of the tray act as guides to prevent misalignment of the sheets or forms as they are successively brought into position in the machine. This feature eliminates the time consuming and difficult task of manually aligning sheets and forms in the typewriter.

In actual operation, the fingers 38 press the forms or sheets 34 closely together about the pointed ends of the fingers so that the upper ends of the latter lie beneath the plane of the outer

face of the outermost sheet. The sheets or forms are loosely compacted with the exception of the two limited zones about the pointed ends of the fingers. Thus the sheet or form elevated out of pressure engagement with the fingers 38 will drop freely without obstruction from the fingers. Fig. 4 illustrates the angularity of the fingers which facilitates dropping of the sheets or forms.

The device 56 is carried by the cover 30 so that both may be moved clear of the tray by merely pivoting the cover to one side. The sheets or forms 34 are then easily placed in position in the tray by grasping a predetermined number in the right hand and dropping the bunch into position as the fingers 38 are pivoted outwardly by grasping the crank 44 with the left hand and turning the crank in a clockwise direction, as when viewing Fig. 2.

Fig. 4 illustrates the manner in which the wings 66 are extended into the slots 64 in the normal position of the device 56. Thus the curvatures 74 of the wings 66 extend into the slots 64 so as to eliminate any space which might constitute an obstruction for sheets or forms being turned out of the machine. The lip 86, while constituting a throat wall to facilitate dropping of sheets or forms into position in the machine, may also function as a deflector when turning relatively flexible sheets out of the machine.

To the cover 30 is riveted an ear 90 which projects beyond the cover sufficiently far to constitute a grip which facilitates opening of the cover.

Without further elaboration, the foregoing will so fully illustrate my invention that others may, by applying current knowledge, readily adapt the same for use under various conditions of service.

I claim:

1. A typewriter feeder adapted to be mounted on a typewriter platen carriage comprising a sheet support located above the platen, guide means for directing successive sheets to the introductory side of said platen, a resiliently urged clamp for holding the sheets on said support, a second support, and a sheet feeding device pivotally and slidably mounted on said second support arranged to be manually brought into frictional engagement with the outermost sheet in the supply for pulling that sheet from said clamp and dropping the sheet into said guide means, said first-mentioned support including a substantially vertically positioned tray having its bottom end opening into said guide means, and the sides of the tray restraining the successive sheets from lateral shifting in their movement into said guide means.

2. A typewriter feeder adapted to be mounted on a typewriter platen carriage comprising an upright plate mounted on said carriage above said platen at an angle to the vertical, a flange-like means on said plate for supporting sheets leaning on said plate, clamp means acting on said sheets for holding the latter against said plate, guide means between said plate and said platen for directing successive sheets to the introductory side of said platen, said plate having side walls restraining the sheets from lateral displacement, a cover hinged to one of said side plates and normally resting on the other side plate, and a sheet feeding device slidably and pivotally mounted on said cover and having a frictional element adapted to be moved into engagement with the outermost sheet in the supply for pulling that sheet from said clamp means and dropping the sheet into said guide means.

3. A typewriter feeder adapted to be mounted on a typewriter platen carriage comprising an

upright plate mounted on said carriage above said platen at an angle to the vertical, a flange-like means on said plate for supporting sheets leaning on said plate, clamp means acting on said sheets for holding the latter against said plate, guide means between said plate and said platen for directing successive sheets to the introductory side of said platen, said plate having side walls restraining the sheets from lateral displacement, a cover hinged to one of said side plates and normally resting on the other side plate, a sheet feeding device slidably and pivotally mounted on said cover and having a frictional element adapted to be moved into engagement with the outermost sheet in the supply for pulling that sheet from said clamp means and dropping the sheet into said guide means, said clamp means comprising pointed fingers bearing against the sheets in the supply, resilient means for yieldingly urging the fingers against the sheet supply, and a crank means connected with said fingers to pivot the same away from said sheets to facilitate placement of a sheet supply on said plate.

4. A typewriter feeder adapted to be mounted on a typewriter platen carriage comprising an upright plate mounted on said carriage above said platen at an angle to the vertical, a flange-like means on said plate for supporting sheets leaning on said plate, clamp means acting on said sheets for holding the latter against said plate, guide means between said plate and said platen for directing successive sheets to the introductory side of said platen, said plate having side walls restraining the sheets from lateral displacement, a cover hinged to one of said side plates and normally resting on the other side plate, a sheet feeding device slidably and pivotally mounted on said cover and having a frictional element adapted to be moved into engagement with the outermost sheet in the supply for pulling that sheet from said clamp means and dropping the sheet into said guide means, said clamp means comprising pointed fingers bearing against the sheets in the supply, resilient means for yieldingly urging the fingers against the sheet supply, and a crank means connected with said fingers to pivot the same away from said sheets to facilitate placement of a sheet supply on said plate, said fingers being bent to provide deflecting runs for guiding the successive sheets into said guide means.

5. A typewriter feeder adapted to be mounted on a typewriter platen carriage comprising a sheet support mounted on the carriage and located above said platen, said sheet support being

in the nature of a tray, a cover for the tray, said cover having a slot, guide means for directing successive sheets to the introductory side of said platen, clamp means for holding the sheets on said support, a sheet feeding device comprising a member located adjacent the inner side of said cover and having a flange extending through said slot to provide a grip, a frictional element mounted on said member, said member being slidably and pivotally related to said cover and said slot being longer than said flange, a weight acting on said flange normally to hold said member closely adjacent said cover, said member being adapted to be pivoted for bringing said frictional element into engagement with the outermost sheet in the supply for elevating that sheet clear of said clamp means and subsequently dropping and pivoting to its normal position for dropping the sheet into said guide means.

20 6. A typewriter feeder adapted to be mounted on a typewriter platen carriage comprising a sheet support mounted on said carriage and located above said platen, said sheet support being in the nature of a tray mounted in an upright position at an angle to the vertical, a flange on said tray for supporting sheets leaning against the tray, clamp means at the lower end of the tray for holding the sheets against the tray, a cover for the tray, said cover being provided with slots, guide means for directing successive sheets to the introductory side of said platen, a sheet feeding device comprising a member located adjacent the inner side of said cover and having flanges extending through said slots to provide a grip, a weight secured to said flanges, a roller carried by said flanges closely adjacent said cover, a frictional element mounted on said member, said member being adapted for pivotal movement to bring said frictional element into engagement with the outermost sheet in the supply for elevating that sheet clear of said clamp means and subsequently dropping and pivoting to its normal position for dropping the sheet into said guide means, said flanges normally resting on the cover edges defining the bottom of said slots and said slots being longer than said flanges so that the latter may be moved upwardly in said slots while removing a sheet from the supply, and a spring element attached to said cover and acting on said member for pivoting the latter to its normal position as said flanges approach the lower ends of said slots, said roller engaging the outer face of said cover during upward and downward movement of the member relatively to said cover.

55 WALTER O. CRITCHFIELD.
